HIGH VOLTAGE ELECTROSTATIC
GENERATOR

Joseph G. Delcav, Baltimore, Md., assignor to
Westinghouse Electric Corporation, East Pitts-
burgh, Pa., a corporation of Pennsylvania

Application December 27, 1944, Serial No. 569,979

6 Claims. (Cl. 171—329)

The present invention relates to X-ray apparatus and particularly to a high voltage electrostatic generator for energizing X-ray tubes with a voltage of the magnitude of 1000 kilovolts and higher.

Apparatus of this general type is now well known in the art and is shown, for example, in Patent No. 2,252,668, granted August 12, 1941, to John G. Trump. As pointed out in such patent, it is essential in apparatus of this kind that a substantially uniform potential gradient be established between the walls of a substantially uniform field surrounding the carrier and the insulating support for the high voltage terminal. To this end a number of equipotential rings in the form of thin shields, each of conductive metal 15 preferably tubular in form to present rounded external surfaces, and spaced from each other in the gap between the terminal and the walls of the tank, are provided.

It is also expedient to control the field due to belt charge by providing a series of conductors extending beyond the width of the belt and located in the same plane as the equipotential rings and disposed on each side of the belt both in its ascent and descent through these rings. To further maintain a uniform potential gradient between the electrode and ground, the equipotential rings have heretofore been connected together by resistances so as to divide the potential.

Although the construction as above noted and as shown in the Trump Patent 2,252,668 will operate satisfactorily for units quite large in size, difficulties are encountered in the construction of apparatus as small and compact as required for commercial purposes. This is due to the fact that in making an apparatus of commercially feasible size, the parts must be spaced closer together without impairment of satisfactory performance. As as result the voltage gradient per inch between the ends of the resistors connecting the equipotential rings becomes greater, causing failure and attendant spark-over near the ends of the resistors where the potential difference is greatest, when the resistors connect each equipotential ring at diametrically opposite joints.

It is accordingly the primary object of the present invention to provide an X-ray generator of the high voltage electrostatic type wherein the potential gradient between the resistor ends is greatly reduced, thus enabling closer spacing of the various parts without impairing operation of the apparatus.

Another object of the present invention is the provision of an X-ray generator of the high voltage electrostatic type in which the resistors for interconnecting the equipotential rings are staggered so as to connect adjacent rings at opposite points in parallel planes, thereby reducing the potential gradient per inch between resistor ends and enabling a more compact generator by closer

spacing of the parts without impairing the efficiency of its operation.

Still further objects of the present invention will become obvious to those skilled in the art by reference to the accompanying drawing wherein:

Figure 1 is an elevational view partly in section along the line I—I of Fig. 2 and showing a high voltage electrostatic generator constructed in accordance with the present invention;

Figure 2 is a sectional view taken on the line II—II of Fig. 1;

Figure 3 is a sectional view taken on the line III—III of Fig. 2;

Figure 4 is an elevational view of an insulator employed in the apparatus of the present invention to space the equipotential rings; and

Figure 5 is a sectional view similar to Fig. 3 but showing in dotted lines the former parallel mounting of the resistors together with the relative increase in spacing due to the staggered mounting of the present invention.

Referring now to the drawings in detail, the apparatus as shown in Fig. 1 comprises a metallic tank 5 preferably filled with gas under pressure of approximately twenty atmospheres. A metallic base plate 6 is supported from the walls of the tank by suitable flanged brackets 7. Extending upwardly from this base plate 6 are a plurality of insulating rods 8 of high dielectric strength, such as glass or the like, which form a ball and socket connection 9 with the base plate 6, and at their top support a ring 10 of conducting material, being fastened thereto through a tensioned screw and nut arrangement 12. A high potential electrode terminal 13 of conductive material, such as brass or the like, and of substantially hemispherical configuration, is in turn supported by the metallic ring 10 concentric with the wall or dome of the cylindrical tank 5, thus providing ample clearance between the tank walls and the high potential terminal 13 carried by ring 10, with the latter being held in place by the insulating rods 8 and by the tension of the belt or charge carrier 14.

As customary in this type of apparatus, the charge carrier is in the form of an endless belt 14 of insulating material, such as rubber fabric, cotton or the like, which passes over a metallic pulley 15 journaled below the base plate 6 and 50 grounded as at 16, with this pulley 15 being rotated by an electric motor (not shown). Journaled above, but insulated from, the top ring 10, is a similar pulley 17 over which the carrier 14 passes, thus providing a parallel ascent and descent for such carrier.

Through a multiple-needle electrode 18, the lower end of the carrier 14 is supplied with a high voltage electrical charge from a suitable source of electric energy, which may comprise a transformer and a rectifier. A similar type

brush electrode 18 disposed at the top of the carrier and connected to the pulley and to the high potential electrode terminal, delivers energy from the carrier 14 to the electrode terminal 13. As shown, an X-ray tube 20 is vertically mounted on the base plate 6 and extends into the hemispherical electrode terminal 13 which serves as the high potential terminal for the tube 20, while the lower grounded end of this X-ray tube extends exteriorly of the tank 5 and terminates in an X-ray target (not shown).

For the purpose of establishing and maintaining a uniform potential gradient down the insulating column formed by the rods 8 between the grounded base plate 6 and the high potential electrode terminal 13, a series of closely spaced metallic rings 22 are provided. Such rings 22, as shown more clearly in Fig. 2, are of tubular form at their periphery and surround the rods 8, as well as the X-ray tube 20 and the ascending and descending run of the carrier 14. These equipotential rings 22 are suitably spaced and insulated from each other by annular insulators 23, as shown in Fig. 4, which fit into recesses provided in the surface of the rings so as to prevent displacement of the insulators. Accordingly, upon tightening of the tensioned screw and nut arrangement 12, the entire assembly forms a rigid column.

To control the field due to carrier charge a series of aluminum conducting rods 24 are secured to about every fourth equipotential ring 22 and extend beyond the width of the carrier 14 in the equipotential plane and spaced a short distance from the latter on each side of the ascending and descending run of the carrier 14. In addition, the same equipotential rings 22 carrying the aluminum voltage gradient control rods 24, also carry insulating rods 25, such as glass or the like, positioned between the rods 24 and the carrier 14 and serve as guides so as to maintain the carrier 14 spaced substantially a uniform distance from the voltage gradient control rods. Each equipotential ring 22 is provided with a metallic projection 26, thus reducing the spacing between the rings 22 at such projection and forming a spark-gap of a definite breakdown potential which enables distribution of the potential from one ring to that next adjacent, should the potential build up too high.

Inasmuch as the operation of the structure thus far described differs substantially in no way from that of the above-noted Patent No. 2,252,668, it is believed unnecessary to herein reiterate the same, since reference may be had to such patent. However, this prior patent discloses that, to divide the potential on the high potential terminal above ground uniformly between the equipotential rings, it is desirable to connect such rings with each other by suitable resistors.

In the prior art such resistors have extended from a point on the periphery of one equipotential ring to a point diametrically opposite on the next adjacent ring, with the next resistor in the series extending from a diametrically opposite point on the same ring to a point diametrically opposite on the next, so that no end of any resistor is connected to the same point on the same equipotential ring and the resistors are thus parallel to each other. Although this arrangement operates satisfactorily, as before mentioned, it results in a very large and cumbersome apparatus because of the spacing required between the parts.

In accordance with the present invention, the resistances which connect each equipotential ring

are staggered, enabling a reduction in the spacing formerly required between the parts resulting in a more compact and commercially practical apparatus. Such construction is shown more clearly in Fig. 3 wherein resistors 27 connect the equipotential rings 22 in a staggered relation, as above mentioned. By this is meant that while one resistor 27 connects a point of one equipotential ring 22 with a point diametrically opposite on the next adjacent equipotential ring 22, the next resistor connects this latter ring at substantially the same point with the next adjacent ring at a diametrically opposite point, thus making a staggered or V-shaped arrangement of the resistors 27 as shown in Fig. 3, in contrast with the parallel arrangement previously employed in apparatus of this type.

By this staggered or V-shaped arrangement of the resistors 27 in accordance with the present invention, the voltage gradient per inch between resistor ends carrying a potential difference is greatly reduced by as much as approximately fifty per cent. This follows despite the fact that even though the spacing between resistor ends having a potential difference is doubled, the voltage therebetween is also doubled. This may be better appreciated when it is considered that the potential gradient E between two flat parallel planes is equal to the voltage V therebetween, divided by the distance D , or

$$E = \frac{V}{D}$$

If now the voltage and spacing between such parallel planes are doubled, the same relationship or proportionality follows, or

$$E_2 = \frac{V_2}{D_2}$$

However, with parallel rings, or ends of the resistors 27 as shown and even when disposed in parallel relation as in the prior art (see Fig. 5), the above noted formula does not hold or

$$E_2 \neq \frac{V_2}{D_2}$$

and by the same token

$$E_2 \neq \frac{V_2}{D_2}$$

nor does any rule of proportionality follow. In other words, whatever the value of the potential gradient E with a given spacing between parallel rings or resistor ends, doubling of the spacing and voltage does not give the same value for E , but on the contrary the potential gradient per inch is reduced with an increase in spacing even when the potential is increased in proportion to the increase in spacing. This may be better appreciated by reference to Fig. 5 wherein the parallel spacing is shown in dotted lines and the staggered arrangement of the present invention in full lines. The resistors 27 are one inch in diameter with a spacing between centers of one and one-quarter (1 1/4) inches at their point of connection with the equipotential rings 22. The spacing at the point of greatest potential stress ("a"—Fig. 5) is accordingly one-quarter (1/4) inch. Assuming a 50,000 volt potential difference therebetween, the above formula, gives

$$E = \frac{50,000}{.25}$$

or 200,000 volts per inch. By staggering the resistors 27, as shown in Fig. 3 and the full lines of Fig. 5, their spacing on centers is doubled to

two and one-half (2½) inches and the spacing between points of greatest potential stress ("b"—Fig. 5) now becomes one and one-half (1½) inches with a potential difference there-between of 100,000 volts. Again applying the above formula

$$E_2 = \frac{100,000}{1.5}$$

which gives a potential gradient of 67,000 volts per inch instead of the 200,000 volts per inch of the prior parallel arrangement.

Accordingly, as will be noted particularly from Fig. 3, the ends of resistors 21 carrying a potential difference are spaced apart so they are connected to substantially a common point on every other equipotential ring 22. This accordingly doubles the spacing previously employed in the art between resistor ends carrying a potential difference therebetween. At the same time since they connect at a point on every other equipotential ring 22 such potential difference is also approximately doubled. However, the potential gradient per inch between such resistor ends is greatly reduced for the reasons above noted over what it is per inch when the resistors are disposed in parallel with each other and connect adjacent equipotential rings at diametrically opposite points. The various parts of the apparatus can accordingly be spaced closer together for the same given potential as a prior art device without in any way impairing the efficient and successful operation of the generator.

It thus becomes obvious to those skilled in the art that a high voltage electrostatic generator is herein provided which is of compact design because of closer spacing between the various parts due to a staggered arrangement of the resistors connecting the equipotential rings.

Although one specific embodiment of the present invention has been shown and described, it is to be understood that further modifications thereof can be made without departing from the spirit and scope of the appended claims.

I claim:

1. A high voltage electrostatic apparatus comprising a high voltage terminal, insulating supporting means for said terminal, a movable endless belt-like charge carrier for transmitting charges between said terminal and ground, a plurality of equipotential conductive surfaces insulatingly spaced from each other closely adjacent said carrier and disposed transversely of the latter, and resistors in staggered relation to each other and connecting said equipotential conductive surfaces to maintain a controlled potential difference therebetween.

2. A high voltage electrostatic apparatus comprising a high voltage terminal, insulating supporting means for said terminal, a movable endless belt-like charge carrier for transmitting charges between said terminal and ground, a plurality of equipotential conductive surfaces insulatingly spaced from each other closely adjacent said carrier and disposed transversely of the latter, and resistors connected to a substantially common point on one of said equipotential surfaces and connected to a diametrically opposite point on each next adjacent equipotential surface to maintain a controlled potential difference therebetween.

3. A high voltage electrostatic apparatus comprising a high voltage terminal, insulating supporting means for said terminal, a movable end-

less belt-like charge carrier for transmitting charges between said terminal and ground, a plurality of equipotential conductive surfaces insulatingly spaced from each other closely adjacent said carrier and disposed transversely of the latter, and resistors connected from a substantially common point on every equipotential surface to a diametrically opposite point on each next adjacent equipotential surface to maintain a controlled potential difference therebetween.

4. A high voltage electrostatic apparatus comprising a high voltage terminal, insulating supporting means for said terminal, a movable endless belt-like charge carrier for transmitting charges between said terminal and ground, a plurality of equipotential conductive surfaces insulatingly spaced from each other closely adjacent said carrier and disposed transversely of the latter, a conductor disposed parallel to and supported by at least one of said conductive surfaces on each side of the ascending and descending path of said carrier in closely spaced relation thereto and of greater length than the width of said carrier to control the electrostatic field due to carrier charge, and resistors connected from a substantially common point on every equipotential surface to a diametrically opposite point on each next adjacent equipotential surface to maintain a controlled potential difference therebetween.

5. A high voltage electrostatic apparatus comprising a high voltage terminal, insulating supporting means for said terminal, a movable endless belt-like charge carrier for transmitting charges between said terminal and ground, a plurality of equipotential conductive surfaces insulatingly spaced from each other closely adjacent said carrier and disposed transversely of the latter, a series of spaced conductors supported by said equipotential conductive surfaces adjacent the ascending and descending path of said movable carrier and of greater length than the width of said carrier to control the field due to carrier charge, and resistors connected from one equipotential conductive surface to a point diametrically opposite on each next adjacent equipotential conductive surface with the resistor ends lying in a common vertical plane on every other equipotential conductive surface to maintain a controlled potential difference between equipotential conductive surfaces.

6. A high voltage electrostatic apparatus comprising a high voltage terminal, insulating supporting means for said terminal, a movable endless belt-like charge carrier for transmitting charges between said terminal and ground, a plurality of equipotential conductive surfaces insulatingly spaced from each other closely adjacent said carrier having a tubular periphery and disposed in a transverse plane about said carrier, a series of spaced conductors supported by said equipotential conductive surfaces adjacent the ascending and descending path of said movable carrier and of greater length than the width of said carrier to control the field due to carrier charge, and resistors connected from a substantially common point on the tubular periphery of each equipotential conductive surface to a diametrically opposite point on the tubular periphery of each next adjacent equipotential surface to maintain a controlled potential difference therebetween.

JOSEPH G. DELCAU.
